United States Patent

Des. 235,841
Patented July 15, 1975

235,841

KNIFE

Henry V. Cremonese, 261 W. 11th St.,
New York, N.Y. 10014

Filed Feb. 6, 1974, Ser. No. 439,890

Term of patent 14 years

Int. Cl. D7—03

U.S. Cl. D7—151

FIG. 1 is a side elevational view of a knife embodying my new design;

FIG. 2 is a side elevation of the opposite side to FIG. 1;

FIG. 3 is a top view of the knife as shown in FIG. 1;

FIG. 4 is a bottom view of the knife shown in FIG. 1;

FIG. 5 is an end elevational view thereof on an enlarged scale as seen from the left of FIG. 1;

FIG. 6 is an end elevational view thereof on an enlarged scale as seen from the right of FIG. 1; and

FIG. 7 is a cross-sectional view thereof on an enlarged scale taken on line 7—7 of FIG. 1.

I claim:

The ornamental design for the knife, as shown and described.
